United States Patent Office

Des. 210,553

Patented Mar. 19, 1968

210,553

LAMP

Henry J. Wilkerson, 211 S. McCrary St.,
Asheboro, N.C. 27203

Filed Dec. 28, 1966, Ser. No. 5,200

Term of patent 14 years

(Cl. D48—20)

Fig. 1

Fig. 2

Fig. 3

Fig. 4

FIG. 1 is a top plan of a lamp showing my new design; FIG. 2 is a side elevational view;

FIG. 3 is a side elevational view 36 degrees removed from FIG. 2.

FIG. 4 is a top plan view of the base taken on line 4-4 in FIG. 2.

The view of the globe as shown in FIG. 2 is repeated every 72 degrees about the globe.

The view of the globe as shown in FIG. 3 is repeated every 72 degrees about the globe.

The characteristic features of my design reside in the specific configuration of the lamp head as shown.

I claim:

The ornamental design for a lamp, as shown and described.
